(57) **ABSTRACT**

A fan of which the blowing efficiency can be increased, the fan including a blade and a bell mouth. The blade rotates around a rotation axis that is along a first direction. The bell mouth includes a staircase structure positioned around the blade along a first plane perpendicular to the first direction. The staircase structure surrounds an opening that spreads toward a blowing direction of the blade.

SUMMARY OF INVENTION

Problem to be Solved by Invention

The problem to be solved by the invention is to provide a fan of which the blowing efficiency can be increased.

Means for Solving Problem

A fan according to an embodiment includes a blade and a bell mouth. The blade rotates around a rotation axis that is along a first direction. The bell mouth includes a staircase structure positioned around the blade along a first plane perpendicular to the first direction. The staircase structure surrounds an opening that spreads toward a blowing direction of the blade.

BRIEF DESCRIPTION OF DRAWINGS

FIG. 1 is a perspective view showing a fan according to an embodiment.

FIG. 2 is a side view showing the fan according to the embodiment.

FIG. 3 is a side view showing a part of the fan according to the embodiment.

FIG. 4 is a schematic view showing a part of a fan according to a reference example.

FIGS. 5A and 5B are schematic views showing a part of the fan according to the embodiment.

FIG. 6 is a simulation result showing characteristics of the fans according to the reference example and the embodiment.

FIG. 7 is a schematic view showing a manufacturing process of the bell mouth.

FIG. 8 is a schematic view showing a fan according to a first modification of the embodiment.

FIG. 9 is a schematic view showing a characteristic of the fan according to the first modification of the embodiment.

FIG. 10 is a schematic view showing a fan according to a second modification of the embodiment.

FIG. 11 is a schematic view showing a fan according to a third modification of the embodiment.

FIG. 12 is a schematic view showing a fan according to a fourth modification of the embodiment.

MODES FOR CARRYING OUT THE INVENTION

Various embodiments of the invention will be described hereinafter with reference to the accompanying drawings.

2

The drawings are schematic and conceptual; and the relationships between the thickness and width of portions, the proportions of sizes among portions, etc., are not necessarily the same as the actual values. The dimensions and proportions may be illustrated differently among drawings, even for identical portions.

In the specification and drawings, components similar to those described previously or illustrated in an antecedent drawing are marked with like reference numerals, and a 10 detailed description is omitted as appropriate.

FIG. 1 is a perspective view showing a fan according to an embodiment.

As shown in FIG. 1, the fan 1 according to the embodiment includes a blade 10 and a bell mouth 20. An X-direction, a Y-direction, and a Z-direction (a first direction) are used in the description herein. The X-direction, the Y-direction, and the Z-direction are mutually-orthogonal.

The blade 10 rotates around a rotation axis R, which is along the Z-direction. The blade 10 includes multiple vanes 11 tilted with respect to the X-Y plane (a first plane) perpendicular to the Z-direction. Three vanes 11 are included in the illustrated example. The number of the vanes 11 is modifiable as appropriate. Air is moved in a blowing direction D1 by the blade 10 rotating.

The bell mouth 20 includes a base part 21 and a ring part 22. The base part 21 has a plate shape spreading along the X-Y plane. The ring part 22 has a circular shape centered on the rotation axis R when viewed along the Z-direction. The blade 10 is located inside the ring part 22.

For example, the fan 1 according to the embodiment is used in an outdoor unit, a ventilation fan, etc.

FIG. 2 is a side view showing the fan according to the embodiment. FIG. 2 shows the cross-sectional structure of the bell mouth. A drive part 12 shown in FIG. 2 is not illustrated in FIG. 1.

As shown in FIG. 2, the drive part 12 is connected to the blade 10. The drive part 12 is, for example, a motor. The rotation axis R of the drive part 12 is connected to the center of the blade 10 in the X-Y plane. The drive part 12 rotates the blade 10 in a rotation direction RD.

In the example shown in FIG. 2, the drive part 12 is located at the opposite side of the blade 10 from the blowing direction D1 side. In other words, the drive part 12 is located at the upstream side of the blade 10. The drive part 12 is not limited to the example; the drive part 12 may be located at the blowing direction D1 side of the blade 10.

The ring part 22 is positioned around the blade 10 at the X-Y plane. The ring part 22 includes an inner circumferential surface 22a facing the blade 10, and an outer circumferential surface 22b at the side opposite to the inner circumferential surface 22a.

FIG. 3 is a side view showing a part of the fan according to the embodiment. FIG. 3 shows the cross-sectional structure of the bell mouth.

As shown in FIG. 3, a staircase structure 23 is provided in the inner circumferential surface 22a of the ring part 22. The staircase structure 23 is positioned around the blade 10 in the X-Y plane.

The staircase structure 23 includes multiple steps 23a arranged along the Z-direction. The steps 23a each are formed along the circumferential direction in the inner circumferential surface 22a. A riser 23b is formed between the steps 23a adjacent to each other in the Z-direction. The distance between each step 23a and the rotation axis R of the blade 10 increases toward the blowing direction D1. In other words, the opening that is surrounded with the staircase structure 23 spreads toward the blowing direction D1.

The outer circumferential surface $22b$ is tilted with respect to the Z-direction so that the thickness of the ring part 22 is substantially constant. A staircase structure is not provided in the outer circumferential surface $22b$. Or, a staircase structure similar to that of the inner circumferential surface $22a$ may be provided in the outer circumferential surface $22b$.

Advantages of the embodiment will now be described.

It is favorable for a fan to have a high blowing efficiency. The blowing efficiency can be represented using the PQ characteristic. The PQ characteristic is represented by the product of the airflow rate and the static pressure during fan operation. For example, even when the airflow rate is constant, the PQ characteristic can be improved by increasing the static pressure.

FIG. 4 is a schematic view showing a part of a fan according to a reference example.

In the fan $1r$ according to the reference example shown in FIG. 4, a staircase structure is not provided in the inner circumferential surface $22a$ of the ring part 22 . The inner circumferential surface $22a$ is flat in the blowing direction $D1$. When the fan $1r$ is operated, air is blown in the blowing direction $D1$ by the blade 10 . At this time, a forward flow $F1$ and a backflow $F2$ are generated in the gap between the blade 10 and the ring part 22 . The forward flow $F1$ is the flow of air in the blowing direction $D1$. The backflow $F2$ is the flow of air in the opposite orientation of the forward flow $F1$. When the flow rate of the backflow $F2$ is large, the static pressure decreases, and the PQ characteristic degrades. It is therefore desirable to reduce the flow rate of the backflow $F2$.

FIGS. 5A and 5B are schematic views showing a part of the fan according to the embodiment.

As described above, in the fan 1 according to the embodiment, the staircase structure 23 is provided in the bell mouth 20 . As shown in FIG. 5A, the staircase structure 23 substantially does not act on the forward flow $F1$. On the other hand, as shown in FIG. 5B, the backflow $F2$ is obstructed by the risers $23b$ of the staircase structure 23 . As a result, the flow rate of the backflow $F2$ can be reduced, and the static pressure can be increased. As a result, the PQ characteristic can be improved.

FIG. 6 is a simulation result showing characteristics of the fans according to the reference example and the embodiment.

In FIG. 6, the horizontal axis is the flow rate (m^3/h). The vertical axis is the static pressure value (Pa). The solid line illustrates the characteristic of the fan 1 according to the embodiment. The broken line illustrates the characteristic of the fan $1r$ according to the reference example. The conditions related to the simulation of FIG. 6 were as follows. The diameter of the blade 10 was 58 cm. A tilt $\theta1$ of the inner circumferential surface $22a$ with respect to the Z-direction (shown in FIG. 3) was 3 degrees. The tilt $\theta1$ corresponds to the angle between a line segment L and the Z-direction. The line segment L was obtained by connecting one end $E1$ and another end $E2$ in the Z-direction of the staircase structure 23 . A tilt $\theta2$ of the outer circumferential surface $22b$ with respect to the Z-direction was 3 degrees.

When compared at the same flow rate, a higher static pressure has a superior PQ characteristic. It can be seen from FIG. 6 that the fan 1 according to the embodiment had a higher static pressure than the fan $1r$ according to the reference example at all flow rates. In other words, the fan 1 according to the embodiment had a better PQ character-

istic than the fan $1r$ according to the reference example. According to the embodiment, the blowing efficiency of the fan can be increased.

Although a part of the blade 10 may be outside the region surrounded with the staircase structure 23 , it is necessary for at least a part of the staircase structure 23 to be positioned around the blade 10 in the X-Y plane. This is because the effect of suppressing the backflow $F2$ is not obtained when the entire staircase structure 23 is located at a position outside the periphery of the blade 10 .

FIG. 7 is a schematic view showing a manufacturing process of the bell mouth.

The bell mouth 20 can be made by injection molding. For example, as shown in FIG. 7, two molds, a mold $M1$ and a mold $M2$, are used. A space SP that corresponds to the shape of the bell mouth 20 is formed when the mold $M1$ and the mold $M2$ engage in the Z-direction. A resin Re is injected into the space SP through an injection inlet IN . The resin Re is cured after the space SP is filled with the resin Re . The bell mouth 20 is made thereby. Subsequently, the mold $M1$ and the mold $M2$ are separated from the bell mouth 20 .

As shown in FIG. 3, the inner circumferential surface $22a$ (the staircase structure 23) and the outer circumferential surface $22b$ of the ring part 22 are not parallel to the Z-direction, and are tilted with respect to the Z-direction. Therefore, when separating the molds $M1$ and $M2$ from the bell mouth 20 in the Z-direction after curing the resin Re , friction can be reduced, and the separation of the molds $M1$ and $M2$ is easy.

The ease of separating the mold $M1$ from the bell mouth 20 increases as the tilt $\theta1$ of the inner circumferential surface $22a$ with respect to the Z-direction increases. From the perspective of the ease of separating the mold $M1$ and the bell mouth 20 , it is favorable for the tilt $\theta1$ to be greater than 2 degrees. On the other hand, when the tilt $\theta1$ is too large, the gap between the blade 10 and the inner circumferential surface $22a$ at the other end $E2$ side may become too wide, and the PQ characteristic may excessively decrease. From the perspective of the blowing efficiency of the fan 1 , it is favorable for the tilt $\theta1$ to be less than 5 degrees.

Similarly, from the perspective of the ease of separating the mold $M2$ and the bell mouth 20 , it is favorable for the tilt $\theta2$ of the outer circumferential surface $22b$ with respect to the Z-direction to be greater than 2 degrees. Although the upper limit of the tilt $\theta2$ is arbitrary, when the difference between the tilts $\theta1$ and $\theta2$ is excessively large, the ring part 22 becomes thicker than necessary in some locations, and an excessive amount of the resin Re is used.

Favorably, each step $23a$ of the staircase structure 23 is tilted with respect to the Z-direction. The tilts of the steps $23a$ with respect to the Z-direction are less than the tilt $\theta1$. It is favorable for the tilts of the steps $23a$ with respect to the Z-direction to be greater than 0 degrees and less than 0.5 degrees. The tilts of the steps $23a$ make it easier to separate the mold $M1$ from the bell mouth 20 . (First Modification)

FIG. 8 is a schematic view showing a fan according to a first modification of the embodiment.

In the fan $1a$ according to the first modification, the staircase structure 23 is formed in a spiral shape centered on the rotation axis R . The spiral is formed so that the steps $23a$ rotate in the rotation direction RD of the blade 10 along the blowing direction $D1$.

FIG. 9 is a schematic view showing a characteristic of the fan according to the first modification of the embodiment.

When the blade 10 is rotated, a backflow $F3$ along the blade 10 is generated as shown in FIG. 9. The static pressure

decreases as the flow rate of the backflow F3 increases. By providing the spiral shape, the risers 23b of the fan 1a according to the first modification are formed to cross the orientation of the backflow F3. As a result, the air of the backflow F3 strikes the risers 23b more easily. By obstructing the backflow F3, the static pressure can be further increased. According to the first modification, the blowing efficiency can be further increased compared to the fan 1.

(Second Modification)

FIG. 10 is a schematic view showing a fan according to a second modification of the embodiment.

In the fan 1b according to the second modification, the Z-direction lengths of the steps 23a of the staircase structure 23 increase toward an opposite direction D2 of the blowing direction D1 as shown in FIG. 10.

For example, the multiple steps 23a include a step 23a1 and a step 23a2. The step 23a1 is positioned further toward the opposite direction D2 side than the step 23a2. A length La1 in the Z-direction of the step 23a1 is greater than a length La2 in the Z-direction of the step 23a2.

Compared to the downstream side of the ring part 22, the gap between the blade 10 and the staircase structure 23 is narrower at the upstream side. The static pressure is easier to increase by increasing the Z-direction length of the part at which the gap is narrow. By increasing the Z-direction length of the step 23a toward the opposite direction D2, the part at which the gap is narrow can be longer, and the static pressure can be increased. According to the second modification, the blowing efficiency can be further increased compared to the fan 1.

(Third Modification)

FIG. 11 is a schematic view showing a fan according to a third modification of the embodiment.

In the fan 1c according to the third modification, the risers 23b of the staircase structure 23 are smaller toward the opposite direction D2 as shown in FIG. 11.

For example, the staircase structure 23 includes risers 23b1 and 23b2. The riser 23b1 is positioned further toward the opposite direction D2 side than the riser 23b2. A size Lb1 of the riser 23b1 is less than a size Lb2 of the riser 23b2.

Compared to the downstream side of the ring part 22, the gap between the blade 10 and the staircase structure 23 is narrower at the upstream side. It is easier to increase the static pressure as the gap becomes narrower. The gap can be made narrower by reducing the size of the riser 23b toward the opposite direction D2. For example, compared to the fan 1, the distance between the blade 10 and the step 23a2 between the risers 23b1 and 23b2 can be reduced. As a result, the static pressure of the fan 1c can be increased. According to the third modification, the blowing efficiency can be further increased compared to the fan 1.

(Fourth Modification)

FIG. 12 is a schematic view showing a fan according to a fourth modification of the embodiment.

In the fan 1d according to the fourth modification, as shown in FIG. 12, the Z-direction length of the step 23a increases toward the opposite direction D2; and the riser 23b becomes smaller toward the opposite direction D2. The blowing efficiency can be further increased by combining the structure of the fan 1b according to the second modification and the structure of the fan 1c according to the third modification.

The embodiments of the invention may include the following Technical Proposals.

(Proposal 1)

A fan, comprising:
a blade rotating around a rotation axis, the rotation axis being along a first direction; and
a bell mouth including a staircase structure, the staircase structure being positioned around the blade along a first plane, the first plane being perpendicular to the first direction, the staircase structure surrounding an opening, the opening spreading toward a blowing direction of the blade.

(Proposal 2)

The fan according to Proposal 1, wherein the bell mouth includes a ring part surrounding the blade along the first plane, the ring part includes an inner circumferential surface facing the blade, and the staircase structure is provided in the inner circumferential surface.

(Proposal 3)

The fan according to Proposal 2, wherein the ring part includes an outer circumferential surface at a side opposite to the inner circumferential surface, and the outer circumferential surface is tilted with respect to the first direction.

(Proposal 4)

The fan according to Proposal 3, wherein a tilt of the outer circumferential surface with respect to the first direction is greater than 2 degrees and less than 5 degrees.

(Proposal 5)

The fan according to any one of Proposals 1 to 4, wherein the staircase structure is formed in a spiral shape centered on the rotation axis, and a step of the staircase structure rotates, toward the blowing direction, in an opposite direction of a rotation direction of the blade.

(Proposal 6)

The fan according to any one of Proposals 1 to 5, wherein the staircase structure includes a plurality of steps, and lengths in the first direction of the plurality of steps increase toward an opposite direction of the blowing direction.

(Proposal 7)

The fan according to Proposal 6, wherein each of the plurality of steps is tilted with respect to the first direction.

(Proposal 8)

The fan according to any one of Proposals 1 to 7, wherein a plurality of risers is formed in the staircase structure, and the plurality of risers becomes smaller toward an opposite direction of the blowing direction.

While certain embodiments of the inventions have been illustrated, these embodiments have been presented by way of example only, and are not intended to limit the scope of the inventions. These novel embodiments may be embodied in a variety of other forms; and various omissions, substitutions, modifications, etc., can be made without departing from the spirit of the inventions. These embodiments and their modifications are within the scope and spirit of the inventions and are within the scope of the inventions described in the claims and their equivalents. The embodiments described above can be implemented in combination with each other.

The invention claimed is:

1. A fan, comprising:
a blade rotating around a rotation axis, the rotation axis
being along a first direction; and
a bell mouth including a staircase structure,
the staircase structure being positioned around the blade
along a first plane,
the first plane being perpendicular to the first direction,
and
the staircase structure surrounding an opening, the opening
spreading toward a blowing direction of the blade,
wherein
the staircase structure is formed in a spiral shape centered
on the rotation axis, and
a step of the staircase structure rotates, toward the blowing
direction, in an opposite direction of a rotation
direction of the blade.
2. The fan according to claim 1, wherein
the bell mouth includes a ring part surrounding the blade
along the first plane,
the ring part includes an inner circumferential surface
facing the blade, and
the staircase structure is provided in the inner circumferential surface.
3. The fan according to claim 2, wherein
the ring part includes an outer circumferential surface at
a side opposite to the inner circumferential surface, and
the outer circumferential surface is tilted with respect to
the first direction.

10

15

20

25

4. The fan according to claim 3, wherein
a tilt of the outer circumferential surface with respect to
the first direction is greater than 2 degrees and less than
5 degrees.
5. The fan according to claim 2, wherein
the bell mouth includes a base part having a plate shape,
and
the base part is provided around the ring part along the
first plane and positioned on a blowing direction side of
the fan.
6. The fan according to claim 1, wherein
the staircase structure includes a plurality of steps, and
lengths in the first direction of the plurality of steps
increase toward an opposite direction of the blowing
direction.
7. The fan according to claim 6, wherein
each of the plurality of steps is tilted with respect to the
first direction.
8. The fan according to claim 1, wherein
a plurality of risers is formed in the staircase structure,
and
the plurality of risers becomes smaller toward an opposite
direction of the blowing direction.
9. The fan according to claim 1, wherein
the bell mouth has a first opening and a second opening,
a direction from the first opening to the second opening is
along the blowing direction, and
a diameter of the second opening is greater than that of the
first opening.
